Attorney

UNITED STATES PATENT OFFICE.

CLEMENT A. TROTH, OF PHILADELPHIA, PENNSYLVANIA, ASSIGNOR TO MARINE EQUIPMENT & SUPPLY COMPANY, OF PHILADELPHIA, PENNSYLVANIA, A CORPORATION OF PENNSYLVANIA.

PROPELLER-SHAFT STRUT.

Application filed August 24, 1926. Serial No. 131,176.

This invention, generally stated, relates to propeller shafting as employed in motor boats, yachts, launches, and the like and has more especial relation to the provision 5 of a strut therefor.

A strut is employed to support the propeller shaft of water craft adjacent the stern thereof, at which part of the boat, said propeller shaft extends downwardly and 10 rearwardly and projects for a considerable distance below the boat hull.

Heretofore it has been difficult and in fact impractical for a manufacturer to carry stock struts, and it has been common 15 practice for boat builders to make a pattern for each design of boat and thereafter have the casting and machining done which obviously is an expensive, slow and altogether unsatisfactory method of procedure. The 20 chief reason for this difficulty is that each style of boat hull requires a strut of special height and heretofore no satisfactory adjustable strut for marine shafting has been devised which could be standardized.

The leading object of the present invention 25 is to overcome the above described disadvantageous features and provide a strut of the character stated which is so arranged, constructed and connected that it may be cheaply manufactured in large quantities, obtained from stock and readily adjusted 30 by unskilled labor to boats of various designs.

A further object of the present invention 35 is to provide a strut of the character stated which is substantially V-shaped to provide a pair of arms each of which is capable of vertical adjustment for the purpose set forth in the leading object.

A further object of the present invention 40 is to provide a strut of the character stated which has a self aligning bearing or hub portion pivotally suspended with respect to V-shaped part of the strut.

Other and further objects of the present invention reside in the provision of general 45 details of construction and in the arrangement, connection and combination of parts as will hereinafter appear.

The invention consists of the novel construction hereinafter described and finally 50 claimed.

The nature, characteristic features and scope of the invention will be more fully

understood from the following description 55 taken in connection with the accompanying drawings forming part hereof, and in which:

Fig. 1, is a view in side elevation of a motor boat equipped with a strut embodying the invention.

Fig. 2, is a view in side elevation of the strut detached.

Fig. 3, is an end view of Fig. 2, certain parts being broken away for the purpose 65 of clearer illustration.

Fig. 4, is an enlarged sectional view of a detail of construction.

Fig. 5, is a view in cross-section of one of the arms shown in Fig. 3. 70

For the purpose of illustrating my invention I have shown in the accompanying drawings one form thereof which is at present preferred by me, since the same has been found in practice to give satisfactory 75 and reliable results, although it is to be understood that the various instrumentalities of which my invention consists can be variously arranged and organized and that my invention is not limited to the precise 80 arrangement and organization of the instrumentalities as herein shown and described.

Referring to the drawings in detail, the strut is shown as being of the V-type, the 85 arms of which are adjustable as to height and the bearing of which strut is adjustable as to angle longitudinally. The bearing is designated by reference numeral 1 for propeller shaft accommodation the latter being 90 designated 2. The upper portion of the bearing 1 is forked or V-shaped in cross-section to form a pair of lugs 3. Having pivotal relation with each lug 3, by means of pivot pin 4 is the lower member 5 of a 95 two-part arm. Each of these members 5 carries at its top, in fixed relation, a tube 6 which may, for instance, be brazed to said member 5. Each tube 6 is internally screw-threaded. Arranged for removable attachment over each tube 6 so as to rest upon the top of a member 5 is the other member 7 of 100 said two-part arms. Each member 7 is hollow and in cross-section is substantially diamond-shaped and the top of each arm is provided with a plate 8 for attachment to the hull of a boat. Each plate 8 is counter-sunk as at 9 to receive the nut 10 of a bolt 11, the 105

lower end of which is screw-threaded to co-operatively engage the tube 6. It is thus apparent that by tightening of nuts 10 the bolts draw upwardly the lower members of 5 the two-part arms including the bearing. In installing a strut of the character above described an adjustment of arm length may be obtained by cutting off the bottom of each hollow arm to obtain desired height, and 10 after the parts are made rigid by taking up on the nuts the protruding parts of the bolts are cut off flush with the arm pads.

This strut is made of manganese bronze castings throughout and emery finished 15 with the exception of the bolts and pins which are tobin bronze. This insures a strong and permanent strut for suspending the propeller shaft beneath the after end of the boat. The need for a stock strut is evident; without this type of strut the boat 20 owner or builder is compelled to make a pattern for each individual boat and have the castings and machine work done in addition. An added advantage of this strut is that instead of having one arm in a vertical manner 25 the V-strut has two arms one bracing the other. The V-strut is intended to fill the need for a strong durable strut that can be obtained from stock and adjusted with a 30 small amount of labor to the boat.

It will now be apparent that I have devised a novel and useful construction which embodies the features of advantage enumer-

ated as desirable in the statement of the invention and the above description and while 35 I have in the present instance shown and described the preferred embodiment thereof which has been found in practice to give satisfactory and reliable results, it is to be understood that the same is susceptible of 40 modification in various particulars without departing from the spirit or scope of the invention or sacrificing any of its advantages.

What I claim is:

1. A strut having a pair of two-part arms arranged V-fashion the upper part of each arm being tubular and provided with a counter-sunk pad to receive a nut, a bolt passing through each arm and having screw-threaded relation with the upper part of each lower arm and a nut for the upper end of each bolt. 45

2. A strut having a pair of two-part arms arranged V-fashion the upper part of each 55 arm being tubular and provided with a counter-sunk pad to receive a nut, a bolt passing through each arm and having screw-threaded relation with the upper part of each lower arm, a nut for the upper end of each bolt, and a bearing having pivotal relation with said arms. 60

In testimony whereof, I have hereunto signed my name.

CLEMENT A. TROTH.
